UNITED STATES PATENT OFFICE.

JOHN SCHAEFER, OF HYDE PARK, ASSIGNOR TO HIMSELF, AND HENRY H. WINDSOR, OF CHICAGO, ILLINOIS.

AUTOMATIC FEEDER FOR PRINTING-PRESSES.

SPECIFICATION forming part of Letters Patent No. 407,840, dated July 30, 1889.

Application filed October 8, 1888. Serial No. 287,502. (No model.)

To all whom it may concern:

Be it known that I, JOHN SCHAEFER, residing at Hyde Park, in the county of Cook and State of Illinois, and a citizen of the United States, have invented a new and useful Automatic Feeder for Printing-PresSES, of which the following is a specification, reference being had to the accompanying drawings, in which—

10 Figure 1 is a plan. Fig. 2 is a side elevation. Fig. 3 is a detail, being a section through a part of the machine at line 3 3 of Fig. 2. Fig. 4 is a side elevation, many of the parts being in a different position from that shown in Fig. 2. Fig. 5 is a longitudinal vertical central section. Fig. 6 is an end view looking to the left of Fig. 2. Fig. 7 is a detail, being a cross-section at line 7 of Fig. 5, looking to the right, showing one-half only of the machine and some parts being omitted. Fig. 8 is a detail, being a sectional view at line 8 of Fig. 1, showing a sheet of paper after it has been acted upon by the rubbers. Fig. 9 is the same as Fig. 8, except that the pressure-bar is raised, allowing the paper to assume a horizontal position.

The object of my invention is to provide devices by means of which single sheets of paper can be automatically fed to a printing-press, which I accomplish as illustrated in the drawings and hereinafter described.

Those things which I claim as new will be pointed out in the claims.

My feeding devices, together with the frame by which they are supported, form an attachment which can be readily connected with and removed from an ordinary cylinder printing-press.

In the accompanying drawings I have shown my invention with such a press, so much only of the press being shown as is necessary to illustrate the use of my invention.

In the following description that part of the machine which is at the left hand of Fig. 2 will be considered as the front and the other end the rear of the machine.

In the drawings, A represents a part of the frame of a cylinder printing-press.

B represents the cylinder.

50 C is the usual cog-wheel on the cylinder.

a a are guides on a rock-shaft b, which shaft can be rocked by devices connected with the press as usual.

D D' are two metal bars, which form the side pieces of the frame which carries my devices. Each of these bars is provided with a slot c, and the rear end of each of these bars is broader than the remaining portion, as indicated in the drawings. These bars are to be bolted to the frame of the press in any suitable manner.

E is an adjustable table on which the sheets of paper F are placed.

G is a cross-piece which extends upward, against which the front ends of the sheets are placed. This cross-piece is provided with two notches d, Fig. 1, to receive grippers.

e is a pressure-bar, which is bent upward, as shown at 1 1, near each end, and then bent out horizontally, as shown at 2 2, and the two ends of this bar are each connected with a vertical rod f, each of which rods slides in a guide g, and the lower ends of the rods are bent at right angles, as shown by 4, Fig. 2.

h is a rock-shaft supported in bearings, on which rock-shaft there are two cams i, one on each side of the machine, which cams are arranged to engage with the under side of the extensions 4 at the lower end of the rods f.

j is a rod fixed in the upper ends of the two uprights k, one on each side of the machine. Each upright k passes loosely through a piece of metal l, which, as shown, is integral with a bar m, which bars slide in guides on the side bars D D'. The lower end of each upright k is provided with a roller, which rollers rest on the extensions 4 on the lower ends of the rods f.

n n are two short rods, which can be vertically adjusted in the heads o o, which heads are adjusted laterally on the rod j. On the lower end of each rod n is a piece of rubber p, or other suitable material, and these rods and pieces p are arranged behind the pressure-bar and constitute pushers to push the sheet of paper toward the grippers, as hereinafter described.

H H are two rods, one on each side of the machine. One end of each rod is pivotally connected to one of the pieces l and the

other end of each rod is supported by and can slide in a support *q*, secured to the bar *D* or *D'*.

5 *r* are adjustable tappets on each rod *H*. *I* is a crank-arm on the shaft of the cylinder.

J is a connecting-bar, one end of which is connected with the crank-arm *I* and the other end is pivoted to the lever *K*, the lower end of which is secured to the rock-shaft *h*.

K' is a lever similar to *K*.

L is a bar bent into the form shown, the ends of which bar are located in the slots *c* in the bars *D* *D'* and slide therein.

15 *M* is a bar pivotally connected at one end to the upper end of the lever *K* and at the other end to one end of the bar *L*.

M' is another bar, connected to the lever *K'* at one end and at the other end to one end 20 of the bar *L*.

N is a shaft pivoted in the vertical parts 6 of the bar *L*. One end 8 of this shaft is bent downward, and is so arranged that it can engage with inclines *uv* on the bar *D'*.

25 *xx* are the upper jaws of two pairs of grippers, which upper jaws are secured to the shaft *N*.

O is another shaft pivoted in the vertical parts of the bar *L*, one end 9 of which is bent 30 forward and carries a roller 10, (see Figs. 1 and 2,) which roller can engage with the under side of a piece *w*, which is secured to the bar *D*.

y y are the under jaws of two pairs of grippers, which under jaws are secured to the shaft *O*.

z is a six-sided collar on the shaft *N*.

11 is a spring arranged to engage with the collar *z*, and the spring holds the gripper-fingers *x* either open or closed.

a' is an incline on the bar *D*. All of the inclines *u*, *v*, and *a'* are adjustable.

P is a cross-bar secured to the frame.

b' is a sliding cross-bar, the ends of which 45 move in slots *c'*.

d' are two pieces turned up at one end and secured to the bar *b'*.

e' are two springs connected at one end to the fixed bar *P* and at their other ends to the 50 sliding bar *b'*.

f' are two angular pieces pivoted to the bar *P*, and arranged so that one end of each is in contact with one edge of the bar *b'*.

55 *g'* are springs which act on the parts *f'*.

h' are levers pivoted to the frame.

i' are connecting-bars, one end of each of which is connected with the lower end of one of the levers *h'* and the other ends to the sliding bar *b'*.

60 *R R'* are two screws, which pass through screw-threaded holes in the arms *j'*, which arms are secured to the table *E*.

S is a ratchet-wheel secured to the upper end of the screw *R*.

65 *T* is a lever pivoted upon the screw *R*, one end of which lever carries a pawl *k'*, which engages with the ratchet-wheel *S*. Upon the

lower end of each screw *R R'* is a bevel gear-wheel *l'*, which wheels engage with bevel-wheels *m'* on a shaft *U*.

70 *n'* is an adjustable stop, against which the short end of the lever *T* can come in contact to limit its movement.

o' is a spring to return the lever *T* to its normal position.

75 *p'* are strips over which the paper passes from the table to the cylinder.

A leading feature of my invention is devices by means of which the pressure-bar *e* is made to press upon the paper and hold it 80 near one end while the pushers or rubbers engage with the paper and are moved forward, carrying a portion of the paper along and making a bend in it, as shown at *q'*, Fig. 8, immediately after which the pressure-bar 85 rises, the rubbers remain in contact with the paper, and the bent portion of the paper falls by gravity, forcing a part of the sheet beyond the line of the remaining sheets, as indicated in Fig. 9, in which position the paper can be 90 caught by the grippers, the rubbers at the same time being raised from the paper, which grippers move back and forth as the cylinder rotates through the action of the crank-arm *I*, connecting-arm *J*, levers *K K'*, and connect- 95 ing-bars *M M'*.

In Fig. 5 the parts are shown in the position last suggested, the grippers having begun their movement toward the cylinder. When the end 8 of the gripper-rod *N* passes 100 up the incline *u*, the upper gripper-jaws will be lifted by the rotation of the shaft *N*, and will come into the position shown in Fig. 4, and will be held there by the spring 11, which is in contact with the collar *z*. At the same 105 time the movement of the sheet will be arrested by the guides *a*, with which its edge will come in contact. The grippers will be carried forward a little farther and then the free ends of the lower jaws of the grippers will be raised 110 a little, as shown in Fig. 4, and will be brought out of the way of the sheet by the movement of the end 9 of the gripper-rod *O* over the incline *a'*. At about the same time the ends 5 of the bar *L* will come in contact with the 115 tappets *r* on the rods *H* and force such tappets into contact with the upper ends of the levers *h'*, and through the connecting-arms *i'* a little movement will be given to the bar *b'* and pieces *d'* attached thereto, which will 120 carry the paper along a trifle if from any cause such movement be necessary, which will be the case whenever the paper has rebounded from the guides *a* or been removed away from them by the jar of the machine. 125 A little side adjustment will also be given to the paper when necessary by one of the pieces *f'*, which are acted upon by the movement of the bar *b'*.

The pressure-bar *e* and the rods *n*, which 130 carry the pieces of rubber *p*, are raised by the rocking cams *i* on the shaft *h*, which cams engage with the under side of the right-angled extension 4 from the rod *f*. When the cams

leave this extension 4, the pressure-bar and the rubbers drop by gravity. The rubbers are operated by the movement of the rods H when the ends 5 of the bar L come in contact 5 with the tappets r on the rods H, and this action takes place just before the time when the upper jaws of the grippers open. Such movement of the rods H moves the sliding bars m in their bearings, and with them the rods k and the rods n, which carry the rubbers. When, by the revolution of the crank-arm I, the bar L and the grippers are carried to the paper to take another sheet, the lower jaws of the grippers will be returned 15 to their proper position by the roller 10, passing under the part w; and the upper jaws will be closed by the passage of the end 8 of the gripper-shaft N over the incline v. The rubbers are moved back by the 20 contact of the ends of the bar L with the tappets s on the bars H, which takes place just before the grippers grasp the projecting sheet. The table which carries the paper is raised a distance equal to the thickness of a 25 single sheet with every revolution of the cylinder by the partial rotation of the screws R R', which are operated by the contact of the lever K' with the outer end of the lever T, which operates the pawl k', which engages 30 with the teeth of the wheel S on the screw R, and by adjusting the stop n' each movement of the lever T and pawl k' can be made to move the ratchet-wheel S a greater or less distance. There is a ratchet-wheel and pawl 35 only on one side of the machine, and through these the screw R is operated, and the screw R' on the other side is at the same time operated through the bevel-wheels l' m' and shaft U. (See Fig. 6.) When all the paper 40 on the table has been used, the table can be lowered by rotating the shaft U, the crank V being shown for that purpose.

By the word "rubbers" I do not mean simply the pieces of rubbers at the lower ends of 45 the rods n, but the devices which act upon and push the paper to form a bend therein, which devices may be called "rubbers" or "pushers."

If desired, springs may be arranged to act 50 on the pressure-bar to increase its pressure on the paper; but ordinarily a bar can be made

heavy enough to perform such office without the aid of springs.

What I claim as new, and desire to secure by Letters Patent, is as follows:

1. The combination of the presser-bar e, having end rods f, the laterally and vertically movable uprights k, carrying a rod j, provided with pushers p, the rock-shaft h, having cams i, acting on the end rods of the presser-bar, and means, substantially as described, for rocking the shaft and moving the uprights.

2. The combination of the pressure-bar e, having end rods f, the rock-shaft h, having cams i to act upon and raise said rods with 65 the pressure-bar, side bars D D', a sliding bar L, supported by the side bars and carrying grippers, the levers K K', connected to the rock-shaft, and arms M M', connecting the levers with the gripper-carrying bar, substan- 70 tially as described.

3. A pressure-bar, as e, the ends of which are secured to vertical rods, as f, having right-angled extensions, as 4, in combination with a rod j, supported by uprights k, which pass 75 through a piece, as l, upon a sliding bar m, rubbers or pushers, such as n, on the rod j, and a rock-shaft h, having cams i, substan- tially as and for the purposes specified.

4. A pressure-bar, as e, the ends of which are secured to vertical rods, as f, having right-angled extensions, as 4, in combination with a rod, as j, supported by uprights, as k, which pass through a piece, as l, upon a sliding bar m, a rock-shaft h, having cams i, rubbers or 85 pushers, as n, and rods H H', provided with tappets r s, substantially as and for the purposes specified.

5. A pressure-bar, as e, supported by rods f, rubbers or pushers, as n, rock-shaft h, and 90 cams i, in combination with the cylinder of a printing-press, crank-arm I, connecting-arm J, levers K K', and rods H H', provided with tappets r s, side bars D D', sliding bar L, shafts N O, carrying grippers, and connecting-arms 95 M M', substantially as and for the purposes specified.

JOHN SCHAEFER.
